EUGENE R. ODEN, OF LANKERSHIM, CALIFORNIA.

PROCESS FOR WATERPROOFING SURFACES.

Application filed April 30, 1928. Serial No. 274,040.

My invention relates to a process to be used for waterproofing surfaces, such as basements, courses between concrete slabs, roofing, concrete reservoirs, etc., and more particularly does it pertain to a process for producing an elastic waterproof membrane between concrete flooring and a covering material, sometimes commercially called "battle-ship linoleum". The capillary attraction of moisture through concrete floors is well recognized, especially where the concrete is built directly upon the earth. In view of the chemical nature of linoleum, same is subject to quick attack by moisture, with a premature 10 rotting, decomposing, swelling, cracking and putrefaction of the material, necessitating an early removal of the material from the floor with attendant great pecuniary loss. Attempts have been made to overcome the 20 herein stated disadvantages, by mixing certain chemicals with the concrete to eliminate its attraction of water through the floor, incident to the relative actions of heat and cold to which the concrete is subjected, but, to the 25 best of my knowledge, such attempts have been unsuccessful. It has been the practice to bond many fabrics together with the air of hot asphalt coats or similar coating materials, and then iron the surface thus treated 30 until the intended close adhesion of these materials is set up with the underlying concrete flooring. Such methods have also failed in their purpose, and in addition thereto same are highly objectionable because of the labor 35 required to be expended in carrying out the several steps; the smoke and other annoyances attending the use of hot asphalts; the muss created; and mainly because of the fact that it has not been possible to bring about 40 evenness of application of the hot coats employed, which is so necessary in avoiding rupture or damage to the expensive linoleum when laid. Nor has it been possible with such methods to prevent the formation of blisters 45 or weak portions in the finished coated surface, and in consequence thereof, water seeping through the concrete soon penetrates through these weak places where it almost instantly attacks the linoleum.

50 An important object of my invention resides in the provision of a novel method of waterproofing which will positively resist the action of hydro-static pressure, or dampness; one wherein the chemical coatings employed are applied while cold; one which may

be practiced quickly and wherein the work can be cleanly performed and at much less cost than has been possible heretofore, and one wherein the materials employed are of a coal tar base, free from the destroying action 60 of caustics, alkali, etc.

Another object of my invention is to provide a method which is conducive to proper sanitation of buildings wherein the method is employed, and wherein the completed waterproof surface or membrane is smooth and without bubbles or blisters and will not injure expensive linoleums when laid thereupon. 65

In the accompanying drawing, the figure 70 is a perspective view of a portion of a concrete floor showing an application of my invention thereto.

In carrying the invention into practice, I first prime the concrete floor A or surface 75 with a cold carbonaceous black elastic coating material or liquid asphalt B, brushing, spraying, or rubbing it in and against the floor A. I then trowel a cold carbonaceous plastic-asbestos-elastic compound C over the 80 aforestated priming coat B. I then apply or lay strips D of heavy felt or tar paper upon the surface thus treated, bringing the edges of the strips into abutting relation to each other, and when this is accomplished, I apply 85 pressure against the strips D, preferably using a heavy roller of approximately two hundred pounds weight, rolling the strips flat against the underlying prepared surface until all air is excluded from beneath the 90 strips so that no air pockets will present themselves, and in order that the upper surface produced by the strips D may be perfectly smooth and without any bubbles or raised places. 95

I then usually follow the previous operation with an application of cold carbonaceous black elastic plastic coating material to the upper surface formed by the strips D, troweling the same over the entire surface, as 100 shown at E, and I lay strips F of felt or tar paper upon this material, abutting their edges, and subject the strips to a rolling pressure as before, and until the desired smoothness of surface is obtained and all air evacuated from under the said strips F, the said strips F being wider than the strips D, so as to span the abutting joints therebetween. 105

The strips D and the strips F mutually produce superposed homogeneous elastic 110

membranes which, when bonded together by the waterprooing compounds herein set forth, result in the formation of a perfect water-sealing means between a concrete floor 5 and a covering material such as the linoleum previously described.

After the floor has been fully prepared, and the parts rolled smooth, the linoleum G is laid upon the underlying receiving surface, 10 but with its longitudinal edges at right angles to the corresponding edges of the said strips D and F.

When my invention is used in connection with roofs, I may employ as many membranes 15 as desired, preferably increasing the number of courses over than previously described, three courses or superposed membranes being desirable.

When the invention is used in connection 20 with concrete reservoirs as a waterproofing therefor, I generally trowel cold carbonaceous plastic compound over the concrete and roll light tar papers onto it as a protection against fouling of the potable water.

25 The plastic coating material herein described may be applied in any thickness that may be found best for the particular work, and seldom need the thickness exceed one-fourth of an inch.

30 I claim as my invention:

1. The herein described process of producing an elastic waterproof membrane upon a face of concrete material, comprising covering the face of the concrete material with a 35 cold carbonaceous elastic coating compound, applying a cold carbonaceous plastic compound over the first said coating; applying strips of sheet material against the second coating while arranging the edges of the 40 strips in abutting relation to each other, and then subjecting the face thus treated to the action of heavy pressure until all air is evacuated from beneath the strips and the upper surface produced by the strips is perfectly 45 smooth while bringing the under surfaces of the strips in firm binding engagement with

the second named cold carbonaceous compound.

2. The herein described process of producing an elastic waterproof membrane upon a 50 face of concrete material, comprising covering the face of the concrete material with a cold carbonaceous elastic coating compound; applying a cold carbonaceous plastic compound over the first said coating; applying 55 strips of paper against the second coating while arranging the edges of the strips in abutting relation to each other; subjecting the face thus treated to the action of heavy pressure until all air is evacuated from 60 beneath the strips and the upper surface produced by the strips is perfectly smooth while bringing the under surfaces of the strips into firm binding engagement with the second-named cold carbonaceous compound; 65 coating the upper surfaces of the strips with a cold carbonaceous plastic coating compound and pressing the strips of paper with their longitudinal edges abutting one another against the last said compound 70 until all air is evacuated from beneath the said strips and the strips present a smooth upper surface, while arranging the second strips so as to span the joints therebetween.

3. The herein described process of producing an elastic waterproof membrane upon a face of concrete material, comprising covering the face of concrete material with a cold elastic compound; troweling a cold carbonaceous plastic compound over the coating compound; applying strips of paper against the second coating while arranging the edges of the strips in abutting relation to each other; and then subjecting the face thus treated to the action of heavy pressure until all air is 80 evacuated from beneath the strips and the upper surface produced by the strips is perfectly smooth while bringing the under surfaces of the strips into firm binding engagement with the second-named cold carbonaceous compound. 85
